Alva G. Rice ^{Inventor}

By Watson E. Coleman ^{Attorney}

UNITED STATES PATENT OFFICE.

ALVA G. RICE, OF DANVILLE, IOWA.

FUSE PLUG.

Application filed June 11, 1923. Serial No. 644,670.

To all whom it may concern:

Be it known that I, ALVA G. RICE, a citizen of the United States, residing at Danville, in the county of Des Moines and State of Iowa, have invented certain new and useful Improvements in Fuse Plugs, of which the following is a specification, reference being had to the accompanying drawings.

This invention relates to improvements in 10 fuse plugs, and the object of the invention is to provide a fuse plug peculiarly designed to be used in connection with the lighting systems of Ford cars and which may be used in place of the usual plug socket that 15 is disposed at the back of the headlight.

A further object is to provide a device of 20 this character which is very simple, which can be cheaply made, and which may be readily applied, and which is further provided with a cover which will normally close 25 the opening through which the fuse is withdrawn.

Other objects will appear in the course 30 of the following description.

25 My invention is illustrated in the accompanying drawings, wherein:—

Figure 1 is a side elevation of an automobile headlight somewhat diagrammatic in character, showing my fuse plug attachment 30 applied thereto;

Figure 2 is a longitudinal sectional view 35 through the fuse plug;

Figure 3 is a side elevation through a slightly modified form of fuse plug partly 40 in section;

Figure 4 is a cross section through the 45 plug with the cover closed;

Figure 5 is a section on the line 5—5 of 50 Figure 7;

Figure 6 is a longitudinal section of the 55 plug, the clamps and the contact members being in elevation;

Figure 7 is a section on the line 7—7 of 60 Figure 5;

Figure 8 is a longitudinal section of the 65 cylinder 10, the clamps 12 and 13, and the contact members 18 and 19, the cylinder being cut away to provide an elliptical opening 11.

Mounted within the cylinder adjacent one 70 end of the opening is a spring clamp 12, and mounted in the cylinder adjacent the other end of the opening is the spring clamp 13.

These clamps may be attached to the cylinder 75 in any suitable manner and are designed

to carry between them the fuse 14 consisting of a glass shell having the usual fuse wire 15 therein and metallic terminals 16.

Disposed in one end of the cylinder 10 is 80 a plug 17 of insulating material through which extend the two spaced contacts 18 and 19, these contacts terminating in heads on the extremities of the plug. This plug projects beyond the case 10 and is provided 85 with the outwardly projecting, oppositely disposed studs 20. The opposite end of the case 10 has inserted therein a hard rubber block 21 which is provided at its outer end with the two contact pins 22 and 23. Each 90 of these pins is provided at its inner end with a head 24 disposed within a cavity in the block and bearing against this head 24 is a spring 25. In the opposite end of each block there is formed a socket 26. The two 95 sockets 26 are designed to receive electric wires 27 and 28. The wire 28 constitutes the end of a conductor 30 disposed within the case 10 and thoroughly insulated, this conductor extending through the lower portions of the clamps or through the case itself without passing through the clamp. Preferably, however, the conductor is disposed within the clamps 12 and 13. This 100 conductor connects to the contact 19, while the contact 18 is connected by means of a wire 31 to the clamp 13, and the clamp 12 is connected by the wire 27 to the member 26 and thus to the contact 22.

Surrounding the case is a cover 33 which 105 is cylindrical in form, loosely embraces the case so as to rotate thereon, and is formed with an elliptical opening 34 conforming in shape and length to the elliptical opening in the case. This cover may be rotated 110 into position to close the opening in the case or rotated to a position to disclose said opening. The case 10 projects beyond the block 21 and is formed with bayonet slots 35 whereby it may be connected to a plug in 115 the electric lighting system. The studs 20 on the plug 17 are adapted to engage with the bayonet slots of a socket which forms the terminals of the wires leading to the electric lamp.

In Figure 3, I illustrate a slight modification where exactly the same construction is employed, except that the wire 30 is omitted and the wires from contacts 19 and 26 are accordingly connected to cylinder 10 so 120 that this cylinder constitutes a conductor. Inasmuch as the construction is of exactly

the same form as that illustrated in Figure 2, the same reference numeral's are used.

- A device of this kind will prevent the bulbs from burning out on automobile and other headlights and is especially adapted for use on Ford cars where the generator feeds to the lamps as well as to the battery and where, therefore, the current fluctuates or varies within relatively large limits.
- 10 The device may be readily disengaged from the fuse clamps and a new fuse put in place whenever the old fuse is burned out. The construction shown in Figure 2 shows the two wire systems such as is used on Ford cars, but I do not wish to be limited to this, as the holder might be made, as before stated, for a one wire system.

In Figures 5, 6 and 7, I illustrate a modified and preferable form of my construction wherein the body 36 is formed of a solid piece of insulating material cut away to form a recess 37 upon the upper face of the plug, the bottom of this recess extending diametrically with relation to the body 36. Disposed below the recess and extending longitudinally through the plug and preferably molded therewith is the metallic conductor 38 which projects slightly beyond one end of the body 36. At its opposite end 30 this metallic conductor is recessed, as at 39, and carries within it the coiled compression spring 40 and this bears upon a pin 41 which is projected out of the end of the recess 39, the wall of this recess 39 being turned over so as to limit the projection of the pin.

Extending in one end of the body 36 is a metallic conductor 42 which extends into the recess 37 and is there connected to the body 40 43 of a clamp 44. This is a metallic clamp of the same character as the clamp heretofore described. Extending into the opposite end of the body 36 is a metallic conductor 45 which is recessed at one end to 45 enclose the spring 46 and the head of a pin 47 against which the spring bears. The inner end of this conductor 45 is electrically connected to the body portion 43 of a second spring clamp having a pair of jaws 44 of the same character as those previously described. Disposed between the jaws and engaged thereby is the fuse proper consisting of an outer glass cylindrical casing 48 having metallic caps 49 at its ends. Disposed within the glass casing is a fuse wire 50 which is engaged with the caps. The caps, of course, have electrical engagement with the metallic clamps 44 and these with the conductors 42 and 45 respectively.

60 The operation of this mechanism is precisely the same as heretofore described for Figures 1, 2, 3 and 4. A rotary cover 51 is mounted upon the cylindrical body 36 so that it may be rotated to close the recess 37 or uncover this recess. This cover 51 bears

at one end against a shoulder 52 formed on a metal sleeve 53 which surrounds the body and over which the cover operates, this sleeve being, of course, cut out above the recess 37. The sleeve at one end has bayonet slots 54 for connection to the plug of a lighting cord and this sleeve 53 terminates short of the other end of the body 36 so that the plug may fit into the socket of the reflector, the end of the body having radial pins 55 engaging with the usual bayonet slots of the usual socket within which the light is disposed in said reflector.

I claim:—

1. A fuse plug for headlights including a cylindrical member having an opening on one face, clamps disposed within said member and immediately opposite said opening, a fuse adapted to be disposed in said clamps, and electrical connections passing from the clamps through the extremities of the member.

2. A fuse plug for headlights including a cylindrical casing having an opening in one face, clamps disposed within said casing and immediately opposite said opening, a fuse adapted to be disposed in said clamps, contact members supported within the ends of the casing and insulated therefrom, and electrical connections from said clamps to said contact members.

3. A fuse plug for headlights including a cylindrical casing having an opening on one face, clamps disposed within said casing and opposite said opening, a fuse adapted to be disposed in said clamps, a pair of axially aligned contact members disposed in the ends of the casing but insulated therefrom, electrical connections extending from each clamp to the adjacent contact member, and an insulated conductor extending entirely through the casing but insulated therefrom.

4. A fuse plug for headlights including a cylindrical body recessed upon one face, a pair of fuse clamps mounted in said recess and adapted to support a fuse between them, a conductor extending inward from one end of the body and engaging one of said clamps, a conductor extending through the other end of the body and engaging the other clamp, said last named conductor being recessed at one end, a spring disposed in said recess, a pin bearing against said spring and projected outward from the end of the conductor, a conductor extending longitudinally through the body below the first named conductor and recessed at one end, a spring disposed in said recess, and a pin engaged in said recess and projected by the spring.

5. A fuse plug for headlights including a cylindrical member of insulating material having a recess in one face, clamps disposed within the recess of said cylindrical member, a fuse adapted to be disposed in said

clamps and electrically engaged therewith, oppositely disposed conductors embedded in the member and electrically connected one with each clamp, a spring projected pin engaged with one of said conductors, and a conductor extending entirely through the member and having at one end a spring projected pin.

6. A fuse plug for headlights including
10 a cylindrical body recessed upon one face, a pair of fuse clamps mounted in said recess and adapted to support a fuse between them, a conductor extending inward from one end of the body and engaging one of
15 said clamps, a conductor extending through the other end of the body and engaging the other clamp, said conductor being recessed at one end, a spring disposed in said recess, and a pin bearing against said spring and
20 projected outward from the end of said conductor, a conductor extending longitudinally through the body below the first named conductor, the last named conductor being recessed at one end, a spring disposed in
25 said recess, and a pin engaged in the recess and projected by the spring.

7. A fuse plug for headlights including a cylindrical body recessed upon one face, a pair of fuse clamps mounted in said recess and adapted to support a fuse between them, a conductor extending inward from one end of the body and engaging one of said clamps, a conductor extending through the other end of the body and engaging
35 the other clamp, said conductor being recessed at one end, a spring disposed in said recess, a pin bearing against said spring

and projected outward from the end of said conductor, a conductor extending longitudinally through the body below the first 40 named conductor, the last named conductor being recessed at one end, a spring disposed in said recess, a pin engaged in the recess and projected by the spring, and a rotatable cylindrical cover mounted upon the body 45 and adapted to be rotated into a position over said recess or into position to disclose the recess, the body having a shoulder against which the cover bears.

8. A fuse plug for headlights including a 50 cylindrical non-conducting body recessed upon one face, a pair of fuse clamps mounted in said recess and adapted to support a fuse between them, a conductor extending inward from one end of the body and engaging one of said clamps, a conductor extending through the other end of the body and engaging the other clamp, a conductor extending longitudinally through the body below the first named conductor, both of 55 said conductors at one end being recessed, springs disposed in said recesses, and pins bearing against said springs and projecting outward from the ends of said conductors, a metallic sleeve surrounding the body 60 and extending beyond the body at the end where the spring projected pins are located, this sleeve at this end having bayonet slots, the body at its opposite end being formed with outwardly projecting, radial pins. 65 70

In testimony whereof I hereunto affix my signature.

ALVA G. RICE.
